DESIGN FOR A VELOCIPEDe BASE PLATE

Eusebius C. Garton, Sheboygan, Wis., assignor to
Garton Toy Company, Sheboygan, Wis.

Application August 21, 1935, Serial No. 58,232

Term of patent 3½ years

To all whom it may concern:

Be it known that I, Eusebius C. Garton, a citizen of the United States and resident of Sheboygan, in the county of Sheboygan and State of Wisconsin, have invented a new, original, and ornamental Design for a Velocipede Base Plate, of which the following is a specification, reference being had to the accompanying drawing, forming part thereof.

Figure 1 is a plan view of the velocipede base plate showing my new design.

Figure 2 is a rear elevation, and
Figure 3 is a side elevation of the same.
I claim:

The ornamental designed for a velocipede base plate, as shown.

In testimony that I claim the foregoing I have hereunto set my hand at Sheboygan, in the county of Sheboygan and State of Wisconsin.

EUSEBIUS C. GARTON.
